UNITED STATES PATENT OFFICE.

LOUIS T. FREDERICK, OF WILKINSBURG, PENNSYLVANIA, ASSIGNOR TO WESTINGHOUSE ELECTRIC & MANUFACTURING COMPANY, A CORPORATION OF PENNSYLVANIA.

PROPELLER.

1,406,364.

Specification of Letters Patent. Patented Feb. 14, 1922.

Application filed December 30, 1918. Serial No. 268,953.

To all whom it may concern:

Be it known that I, LOUIS T. FREDERICK, a citizen of the United States, and a resident of Wilkinsburg, in the county of Allegheny and State of Pennsylvania, have invented a new and useful Improvement in Propellers, of which the following is a specification.

My invention relates to air screws or propellers for aircraft, and it has for its primary object the provision of a composite propeller possessing certain desirable characteristics.

More particularly my present invention relates to a propeller having a working body portion comprising superimposed layers of fibrous sheet material, impregnated with a hardened binder, in which the layers are preferably disposed in planes substantially parallel to the faces of the hub. One of the objects of this invention consists in providing a propeller of this character in the form of a hollow body, of the above indicated composition, enclosing a permanent core of wood, cork or other suitable material whereby the weight of the propeller may be decreased.

Heretofore, propellers formed entirely of wood have been undesirable because of their warping, under climatic changes, and their likelihood to splinter and pit during use. Satisfactory propellers composed solely of fibrous material and a hardened binder have been made which are not subject to these criticisms but such propellers are, under present conditions, more expensive because of the cost of materials. By practising my present invention, I provide a propeller having an inexpensive inner body portion or core covered by an outer casing or shell of a material which will effectively and satisfactorily withstand all operating conditions.

Another object which I have in view is the provision of a simple and rapid means of assembling and forming a propeller of this character.

With these and other objects in view, my invention will be more fully described, illustrated in the drawings, in the several views of which corresponding numerals indicate like parts, and then particularly pointed out in the claims.

Fig. 1 is a front elevation of a propeller constructed in accordance with my invention; Fig. 2 is a top plan view of the propeller, the core being shown in broken lines, Fig. 3 is a diagrammatic section illustrating

the method of assembling the component parts of the propeller, the section being taken substantially on the line III—III of Fig. 2, and Figs. 4 and 5 are plan views of properly shaped layers of fibrous material which may be employed in the propeller construction and which, in practice, will occupy substantially the positions indicated by the lines IV—IV and V—V respectively of Fig. 2.

In practising my invention, a permanent core of wood, cork or other suitable material of proper shape and size may be formed in any desired manner and may be enclosed in a covering of fibrous material, in sheet or other preferred form. This fibrous material may preferably be impregnated with a suitable binder before it is applied to the core although this impregnation may be accomplished after the propeller is assembled, if desired. The assembled propeller may then be cured in any suitable manner, usually in a mold, in such a way as to permanently harden the binder and compact the materials constituting the propeller.

More particularly, I prefer to follow a process disclosed in a copending application filed by D. A. Dickey, Dec. 30, 1918, Serial No. 268,949 and assigned to the Westinghouse Electric & Manufacturing Company, in which fibrous sheet material, such as duck or other woven fabric, paper or cotton batting, is impregnated with a suitable binder, such as a phenolic condensation product, and dried to drive off the solvent employed in the binder without affecting the properties of the binder. This sheet material, as fully disclosed in the above-referred-to application, is then cut into layers of suitable shapes and sizes so that, when the layers are superimposed, in proper successive positions relative to each other, a substantially propeller-shaped body will result.

When practising my invention, I provide the layers 1 in the same manner as that disclosed in the above-referred-to application but cut or otherwise form openings 2 in certain of the layers in such manner that, when the layers are assembled, a space of proper size and shape for the reception of a core 3 may be provided. In assembling my propeller 4 the various layers 1 are superimposed in proper positions relative to each other and about the previously shaped core 3 to provide a propeller-shaped body

completely enclosing the core, after which the assembled body is compressed and cured. If the binder employed is a phenolic condensation product, the curing may best be performed by subjecting the assembled body to heat and pressure, in a mold of proper design, to strongly compact the material and transform the binder to its solid and substantially insoluble and infusible state.

10. Obviously, a propeller constructed in accordance with my invention is as resistant to injury, under operating conditions, as a propeller constructed entirely of fibrous material and a binder and, at the same time, 15 it may, under present conditions, be more economically manufactured and may, in some instances, be somewhat lighter in weight.

Although I have illustrated and described but one method of constructing a propeller 20 in accordance with my invention, it will be appreciated that other methods of preparing the materials, including both the core and the sheet material, and of assembling them, may be practiced without departing from the 25 spirit of my invention. For this reason, no limitations are to be imposed upon my invention other than those set forth in the claims.

I claim as my invention:

30. 1. A propeller comprising a non-metallic core and a surrounding body of molded material.
2. A propeller comprising a non-metallic core and a propeller-shaped body surrounding the core and formed of composite material molded thereto.
3. A propeller comprising a non-metallic core and a body of fibrous material impregnated with a hardened binder molded about the core.
4. A propeller comprising a core of wood

and a body of fibrous sheet material impregnated with a hardened phenolic condensation product molded about the core.

5. A propeller comprising a core and a 45 propeller-shaped casing molded about the core and comprising superimposed layers of fibrous sheet material impregnated with a hardened binder.

6. A propeller comprising a core and a 50 propeller-shaped casing molded about the core and comprising superimposed layers of fibrous sheet material impregnated with a hardened binder, the sheets being disposed in planes substantially parallel with 55 the faces of the propeller hub.

7. A propeller comprising a core of wood and a plurality of sheets of impregnated fibrous material superimposed upon each other and enclosing the core, the sheets being 60 impregnated with a phenolic condensation product which has been hardened by heat and pressure.

8. The method of forming a propeller which comprises providing a non-metallic 65 core and molding fibrous material impregnated with a binder about the core.

9. The method of forming a propeller which comprises shaping a core, cutting a binder-impregnated sheet of fibrous material 70 into layers of such shapes and sizes that, when properly superimposed, they will form a substantially propeller-shaped body enclosing a chamber of proper shape and size to receive the core, superimposing the sheets 75 about the core and subjecting the body thus assembled to heat and pressure to compact the fibrous material and harden the binder.

In testimony whereof, I have hereunto subscribed my name this 21st day of Dec., 80 1918.

LOUIS T. FREDERICK.
